UNITED STATES PATENT OFFICE.

HERBERT R. NEVENS, OF HARTFORD, CONNECTICUT, ASSIGNOR TO NEVENS-WALLACE TRAIN CONTROL COMPANY, A CORPORATION OF MASSACHUSETTS.

TRAIN-STOP MECHANISM.

1,305,738.

Specification of Letters Patent. Patented June 3, 1919.

Application filed May 26, 1914. Serial No. 841,069.

To all whom it may concern:

Be it known that I, HERBERT R. NEVENS, a citizen of the United States, residing at Hartford, county of Hartford, State of Connecticut, have invented certain new and useful Improvements in Train-Stop Mechanism, of which the following is a specification.

This invention relates to the positive control of railroad trains and the like for the purpose of preventing the neglect or disobedience of the usual signals employed in such systems.

My present invention has for its object 15 to provide an engine equipment in which the valve controlling the application of the brakes will open with the air pressure in the train line pipe to secure a positive application of the brakes under all conditions 20 and which valve will be normally held closed against the pressure. I attain this object by the use of a valve normally sealing the train line pipe but freely releasable to open fully upon any actuation thereof so as to 25 make available at all times the full setting pressure in the air system of the train.

The construction and operation of my invention will be more fully disclosed in the specification that follows. In the drawings 30 forming a part of that specification I have shown as an illustrative embodiment a form of equipment which not only clearly illustrates the principles involved but is in itself a construction proven to be satisfactory in 35 practice. Throughout the specification and drawings like reference numerals are correspondingly applied and in these drawings:

Figure 1 is an elevation of an engine equipment in accordance with my invention.

Fig. 2 is a vertical section at right angles to Fig. 1.

Fig. 3 and Fig. 4 are sections similar to Fig. 1 showing the valve in its two positions.

I have indicated at 1 a box or casing 45 adapted to be attached to a truck on the engine so as to bring its trip arm 2 in position to strike a trip along the trackway when said track trip is set in danger position. The trip 2 is adjustably held in a sleeve 3 50 by a slot and bolt connection 4 which permits a relative vertical adjustment of the trip to shorten or lengthen its effective trip arm. The sleeve 3 is rigidly fastened on a transverse rock shaft 5 journaled in the lower end of the box. The box at this end

has a lateral casing 6 in which the sleeve is disposed so as to position the trip eccentrically of the box. The rock shaft near its opposite end has a cam 7 provided with a central curved face 8 and lateral curved faces 9 and 10. The face 8 is disposed in a plane above that of the faces 9 and 10 when the cam is in its normal position. When so positioned the central face 8 receives and supports a cam roll 11 pinned at 12 in the lower bifurcated end 13 of a valve item 14 reciprocable in a vertical guide and valve casing 15 secured to the box. The lateral faces 9 and 10 constitute locking depressions for the roll 11 when the trip has been actuated in either direction to effect a partial rotation of the rock shaft with a consequent oscillation of the cam and lowering of the valve stem.

The lowering of the valve stem 14 is effective to unseat a valve 16 guided within the tubular portion of the stem and normally closing a valve port 17 in the head 15¹ of the valve casing 15. The valve is held to its seat against the pressure in the train line pipe 18 by a coiled spring 19 interposed between the valve and the base of the tubular portion of the stem 14.

The train line pipe 18 supplies air under pressure to the valve chamber 20 of the casing head 15¹. The pipe 18 is threaded into a nipple 21 which connects with the head 15¹ of the casing. When the valve is released it opens with the pressure to its fullest degree. The air passes through the port 17 and through a laterally disposed port 17¹ at the upper end of the stem 14 out into a delivery pipe 22 connected with the exhaust of the valve by a nipple 23 on the opposite side of the casing head.

The delivery pipe 22 connects preferably with an independent speed governed relief control (not shown) whereby an application of the brakes is secured in direct proportion to the speed at which the train is traveling at the time when the valve is open.

In use the trip 2 is normally disposed in the position shown in Fig. 3. In this position the valve 16 is held closed against the train line pressure by the cam face 8 which is disposed in supportive relation to the valve stem. When the trip 2 strikes the track trip an actuation is given it effective to rock the shaft 5 and move the cam face 110

8 of the cam 7 out from under the stem. The support for the stem being thus removed, the stem lowers by its own weight, unseating the valve 16 and permitting passage of the air under pressure from the train line pipe 18 to the exhaust pipe 22 (see Fig. 4). The stem is lowered gradually, the roll 11 riding down either the face 9 or the face 10 (depending upon the direction in which the train is traveling) until it rests against the shoulders 9¹ and 10¹ thereof. When so positioned the trip is locked and in the construction shown must be reset manually. This is considered a desirable feature in train stop equipment for the reason that it requires the engineer to descend from the cab and reclose the valve before the train can proceed. Obviously however a resetting arrangement operative from the cab could be provided if considered desirable.

Various other modifications in the form and construction of my device may obviously be made without departing from the spirit of my invention if within the limits of the appended claims.

What I therefore claim and desire to secure by Letters Patent is:

1. In combination, a casting having a tubular portion providing a guide and having communicating passages extending from said guide, a chambered valve stem slidable in said guide, a valve in the chamber of said stem and controlling the communication of said passages, a spring confined between said valve and one end of said tubular portion, and a movable support for said stem.

2. In combination, a member having an axial bore and having an intake and an exhaust port opening into said bore, a chambered valve stem slidable in said bore and

having a bifurcated end, a valve in the chamber of said stem and controlling said ports, a spring confined between said valve and the opposite wall of said chamber, a roll mounted between the furcations of said stem, and a movable support for said stem including a plurality of faces and all of said faces concave to receive said roll in the use of the device.

3. In combination, a casting having a depending tubular portion providing a guide and having laterally extending tubular portions providing passages communicating with each other through said guide, a chambered valve stem slidable in said guide, a valve in the chamber of said stem and controlling the communication of said passages, a spring confined between said valve and one end of said tubular portion, and a combined support and lock for said stem.

4. In combination, a casting having a depending tubular portion providing a guide and having laterally extending tubular portions providing passages communicating with each other through said guide, a chambered valve stem slidable in said guide, a valve in the chamber of said stem and controlling the communication of said passages, a spring confined between said valve and one end of said tubular portion, and a combined support and lock for said stem having a central supporting face and a pair of opposed locking faces disposed in a plane below that of the supporting face.

In testimony whereof I affix my signature in presence of two witnesses.

HERBERT R. NEVENS.
